UNITED STATES PATENT OFFICE.

MICHAEL J. MILMOE, OF CHICAGO, ILLINOIS, ASSIGNOR TO F. B. REDINGTON CO.,
OF CHICAGO, ILLINOIS, A CORPORATION OF ILLINOIS.

COUNTER.

1,315,738.

Specification of Letters Patent.

Patented Sept. 9, 1919.

Application filed June 14, 1915. Serial No. 33,898.

To all whom it may concern:

Be it known that I, MICHAEL J. MILMOE, a citizen of the United States, residing at Chicago, in the county of Cook and State of Illinois, have invented certain new and useful Improvements in Counters, of which the following is a specification.

This invention relates to a device for counting articles that pass a given point in succession, and is intended for general use wherever a counter of this character is desirable. The invention consists substantially in the combination and arrangement of parts hereinafter described, illustrated in the accompanying drawings, and more particularly set forth in the appended claims.

In the drawings—

Figure 1 is a front elevation of a counter embodying this invention. Fig. 2 is an end elevation with the locking arm partly broken away looking toward the right in Fig. 1.

Fig. 3 is an end elevation looking toward the left in Fig. 1, with parts in section.

Fig. 4 is a fragmentary end elevation similar to Fig. 3 but showing the casing unlocked and slightly opened.

Fig. 5 is a section on line 5—5 of Fig. 2.

Fig. 6 is a top plan view of the lower section of the counter, with the upper section removed.

Fig. 7 is a bottom plan view of the upper section of the counter removed from the lower section.

Fig. 8 is a sectional elevation on line 8—8 of Fig. 5.

Fig. 9 is a fragmentary sectional view similar to Fig. 8 but showing the casing partially opened.

Fig. 10, 11 and 12 are details of one of the driving pinions.

Fig. 13 is a side elevation of one of the counter units.

Fig. 14 is a section on line 14—14 of Fig. 13.

Fig. 15 is a fragmentary sectional view on line 15—15 of Fig. 14.

Fig. 16 is a perspective of one of the driving pinions.

Fig. 17 is a side view of the driving pinion which is fast on the driving shaft.

Fig. 18 is a side elevation of the star wheel for operating the counter.

Fig. 19 is a side view and Fig. 20 a sec-

tion of one of the disks for holding the star wheel together.

Fig. 21 is a section on line 21—21 of Fig. 18.

Figs. 22 and 23 are detail views of one of the arms of the star wheel shown in Fig. 18.

Fig. 24 is a section on line 24—24 of Fig. 22.

Fig. 25 is a perspective of the driving shaft; and

Fig. 26 is a perspective of the latch.

In the drawings, the numeral 1 designates an upper section and the numeral 2 a lower section of a casing for inclosing the operating mechanism of the counter. The lower section 2 of the casing comprises a bottom portion 3 and a side wall 4 extending upwardly from one edge of the bottom. End walls 5 of triangular shape, as shown in Figs. 2, 3 and 8, close the ends of the lower portion of the casing and have their upper edges extending from the upper portion of the wall 4 to the upper portion of the slightly upturned part 6 of the bottom 3.

The upper edges of these parts 4, 5 and 6 all lie in a single plane so that they can be finished off by a single tool, such as is used in a milling machine or a planer. The upper section of the casing comprises a circular wall 7 and end walls 8 which form a casing having a general semi-cylindrical shape.

The two lower edges of the circular wall 7 and the lower edges of the walls 8 lie in the same plane and are of the proper dimensions to fit closely the upper edges of the parts 4, 5 and 6 of the lower section of the casing, as shown best in Fig. 8. When the two sections 1 and 2 are brought together it is apparent that a complete inclosure will be formed having a flat bottom and one flat side and having a removable cover semi-cylindrical in shape.

The meeting portions of both of these sections lie in a single plane so that they can be conveniently machined off to make a substantially moisture proof fit so that the closed casing practically excludes all moisture which otherwise would find access to the operating parts of the counter. A pair of lugs 10, Figs. 2, 3, 4, and 7, project downwardly from one side of the upper section 1 of the casing and are positioned outside of the end walls 8 thereof. These lugs therefore extend over the end walls 5 of the

65

70

75

80

85

90

95

100

105

lower section when the two sections are in closed position. Each of the lugs 10 is provided with a slot 11 which forms a hook adapted to engage the projecting ends of a 5 rod 12 carried in projections 13 secured to the lower portion of the casing section 2. In this way a detachable hinge connection is formed between the upper and the lower sections of the casing. It is apparent from 10 an inspection of Fig. 4, that when the upper section 1 of the casing has been opened somewhat farther than is shown in this figure, this portion may be moved to the left and thus disconnected from the lower 15 portion of the casing. Secured to the rear portion of the upper section 1, is a second pair of lugs 15 projecting downwardly from the casing in a manner similar to that of the lugs 10 and forming latching devices to 20 hold the two sections together. A latching bar or rod 16, see especially Fig. 26, is rotatably mounted in the end walls 5 of the lower section 2. This latch bar 16 has connected to each end thereof a projecting portion 17 which is partially cut away to leave the portion 17 of the shape of a segment of a circle in cross-section. As shown in Fig. 25 4, the portion 17 may be turned to a position to permit the lug 15 to pass the latch bar in 30 closing the casing. After the casing is closed, the latch bar may be rotated to bring the bar 17 into the position shown in Fig. 3, the part 17 entering an opening 18 in the shape of a segment of a circle formed 35 in the lug 15. In this way the two parts of the casing are securely latched in closed position. In the construction of the casing, the two sections 1 and 2 are first machined to fit one another and then clamped together while the holes for the reception of 40 the latch member 16 and the hinge rod 12 are drilled, the drill being positioned to cut the opening 18 in the lug 15 at the same time that it drills the hole for the bar 16 in the 45 lower portion of the casing. In this way it is made certain that the opening 18 will be in the proper position to hold the parts 1 and 2 tightly closed. The portion of the lugs 11 at one side of the holes thus drilled 50 are later cut away to form hooks 11.

A shaft 20, Figs. 4, 5 and 8, is mounted near the center of curvature of the upper section of the casing and carried by this shaft and free to rotate thereon, is a series 55 of counting units designated generally by the numeral 21, Figs. 5, 6, 13 and 14. Each counting unit is rigidly mounted on a collar 22 which forms a hub, for carrying the various parts of the unit. These hubs, as shown 60 in Fig. 5, are free to turn on the shaft 20 and are positioned end to end with one another. The collar 22 is reduced at each end forming a projecting portion near the middle thereof to provide shoulders for holding 65 the parts of the counting unit in position.

Each counting unit comprises a gear 23, a numeral wheel 24, a Geneva gear 25, and a single-toothed bar 26. The numeral wheel 24 is built up on a thin, sheet metal, cup-shaped disk 27 and a metal rim 28 which surrounds the wheel and carries the numerals ranging from zero to nine stamped thereon. The parts of the counting unit fit tightly on the hub 22 and are secured together by rivets and spacing members 29, so that when the 70 parts are all assembled, they form a rigid unit. Washers 30 surround the shaft 20 at each end thereof to space the counting units from the ends of the casing and properly hold them in position. Mounted in the 75 angle between the bottom 3 and the wall 4 of the lower section 2 of the casing, is a rod or shaft 31 which carries the driving pinions for the counting units. One of these pinions is shown in detail in Figs. 10, 11, 80 12 and 16. Each pinion includes a hub or collar 32 having one end reduced to receive three pinions, 33, 34 and 35. Each of the pinions 33, and 34, carries four teeth, as shown in Fig. 10, and pinion 35 is provided 85 with eight teeth, as shown in Fig. 11. In constructing the complete driving pinion, the gear 33 is first forced tightly unto the collar 32. The pinion 34 is then placed on the collar 32 with its teeth alternating with the teeth of the pinion 35, and the pinion 35 is lastly placed on the collar 32 with its alternate teeth positioned adjacent the teeth of the pinion 34 and the other teeth opposite the teeth of the pinion 33. The relative 90 position of the pinions is seen clearly by an inspection of Fig. 16. After all of the pinions are in position on the collar 32, the end of the collar is slightly upset to hold the pinions rigidly in position relative to one another and to the supporting sleeve. By means of this built up construction the completed pinion may be very cheaply constructed from steel, each pinion being 95 stamped out separately which would be impossible if the entire device were constructed of one piece. The shaft 31 extends outwardly from one end of the casing, as shown 100 in Fig. 5, and is surrounded by a sleeve 36. The end of the shaft 31 may be upset to hold it rigidly to the sleeve 36 to rotate therewith, or the shaft may be allowed to remain free relative to this collar. The driving pinions are not operated by the shaft 31 and hence it is immaterial whether this 105 shaft rotates or is stationary. A single eight-toothed pinion 37, Figs. 5 and 17, is rigidly secured to the end of the collar 36 to rotate therewith and is in position to mesh with the gear 23 of the counting unit which occupies the units position in the assembled counter. The four-toothed pinion 33 of the first complete driving pinion is positioned 110 opposite the Geneva disk 25 of the counter in units position, and the four-toothed pin- 115

120

125

130

ion 34 is opposite the one-toothed bar 26 of the same counter. The eight-toothed pinion 35 is opposite the gear 23 of the counter in the tens position. When the casing is closed, the gears 23 mesh with their corresponding driving pinions 37 and 35 and at the same time two of the teeth on the pinion 33 lie against the periphery of the Geneva disk 25 to prevent rotation of this pinion, while one of the teeth on the pinion 34 projects toward the counters in position to be struck by the tooth on the bar 28 when this bar has rotated to a point opposite the shaft 31. As will be seen by reference to Figs. 13 and 14, the opening 40 in the Geneva disk 25 is removed a distance equal to the width of one tooth from the front edge of the tooth carried by the bar 26. It will thus be apparent that when the one-toothed bar 26 strikes the projecting tooth on the pinion 35, the opening 40 will be in position to receive the tooth on the pinion 33, so that the entire driving pinion will be permitted to be rotated an amount equal to the width of one tooth by the bar 26. The rotation of the driving pinion by the bar 26, as has been seen, will turn one of the teeth 33 into the opening 40 in the Geneva disk, and since both the bar 26 and the Geneva disk 25 rotate in unison with the counter, the driving pinion will be further rotated a distance equal to the width of one tooth by the Geneva disk. It will thus be apparent that for each rotation of the counter in the units position, the entire built up driving pinion will be rotated a distance corresponding to the width of two teeth. Since the pinion 35 which is carried by this driving pinion meshes with the gear 23 carried by the counter in the tens position, this tens counter will likewise be rotated a distance corresponding to the width of two teeth for each revolution of the units counter. Each gear 23 is provided with twenty teeth and each counter, as has been stated, is provided with ten numerals, so that the rotation of a counter a distance corresponding to two teeth will move the counter a distance equal to that occupied by a single numeral. The parts are so positioned that the rotation of the tens counter from the units counter takes place simultaneously with the movement of the numerals on the units counter which changes the numeral in the reading position from nine to zero. The units counter is driven directly from the sleeve 36 and since the pinion 37 carries eight teeth, the units counter will be moved a distance corresponding to one numeral for each one quarter turn of the sleeve 36. To make certain that the sleeve 36 will turn a complete one quarter of a revolution at each operation, this sleeve is provided with a squared portion 41 and an extension 42 is provided on the end of the casing 2 which incloses a spring pressed plunger 43 adapted to bear against the squared portion 41 of the sleeve 26 as shown in Fig. 3. A spiral spring 44 presses the plunger 43 into contact with the squared portion 41. The spring 44 is held under compression by 70 means of an adjustable collar 45 surrounding a portion of the plunger 43 and held in position by a cotter pin 46. This cotter pin lies in a groove 47 in the collar 45 and a series of holes 48 is provided in the casing 75 for adjusting the cotter pin back and forth to regulate the tension in the spring 44. It will be noted that throughout the structure no screws or threaded connections are used for holding the parts together. A counter 80 of the character disclosed in this invention must be mounted upon a machine and subjected to vibration which has a great tendency to loosen screw connections, and it is for the purpose of avoiding this defect 85 that the parts are held in position by other means than screws. This idea has been carried out in the above described adjusting mechanism for the tension of the spring 44. 90

It is apparent from the construction of the casing that the driving pinions and the counter gear wheels will be moved out of and into mesh respectively when the casing is opened and closed. For this reason it is desirable that the gears should be locked in position when the casing is opened in order that they may again properly mesh when the casing is closed. The latch bar 16 is arranged to accomplish the locking of the driving pinions, as shown in Fig. 9. The bar 16 is cut away on one side in the central portion, leaving an eccentric segment 50, Figs. 8, 9 and 26. Bar 16 is rotated by means of a lever or arm 51 and when this arm is in the upper position, shown in Fig. 8, the casing is locked in its closed position. In this position of the arm, the eccentric segment 50, as shown in Fig. 8, is turned upwardly out of contact with the driving pinions. As shown in Fig. 9, when the arm 51 is turned downwardly to unlatch the casing, the eccentric segment 50 is rotated into its lower position and enters the opening between the teeth on the driving pinions and locks these pinions from movement so long as the arm 51 remains in the downward position. In this way, the driving pinions are automatically locked when the casing is unlatched and automatically unlocked when the casing is again closed and latched. The arm 51 may be secured in its locking position by means of a cotter pin or padlock passing through the opening 52 therein, and lying in the depression or notch 53 which is cast in the casing in proper position to register with the opening 52 when the arm 51 is in locking position. The arm 51 carries a pin 54 adapted to strike against a projection 55 on the casing 2 and the lug 15 on the casing 1, to limit the movement of the arm 51. 100 105 110 115 120 125 130

For the purpose of preventing an accidental rotation of the numeral wheels while the casing is open, each wheel is provided with a spring detent 56 having a rounded tooth 57 yieldingly held in contact with the teeth of the gears 23, as shown in Fig. 9. By means of these spring detents the numeral wheels are prevented from accidental rotation, but when sufficient force is exerted upon them to rotate them, the spring detents will be moved outwardly and the wheels permitted to be rotated for adjustment and setting. When the casing is closed, the numeral wheels are prevented from accidental rotation as previously described, by the Geneva lock mechanism, and it is therefore unnecessary for the detents 56 to contact with the gears 23 under these conditions. The detents 56 are therefore provided with projections 58 which contact with the eccentric segment 50 on the shaft 16 and hold the teeth 57 out of contact with the gears 23 when the casing is closed. It is thus seen that mechanism is provided for automatically locking the numeral wheel gears against accidental rotation when the casing is opened and for unlocking these gears upon the casing's being closed.

The wall 7 of the upper casing 1 is provided with an opening 60, Figs. 1 and 8, through which the readings of the numeral wheels are made. This opening is covered by a glass plate 61 held in position by downwardly turned portions 62 of the name plate 63 secured to the front of the casing. The space between the downwardly turned portion 62 and the glass 61 is filled with putty or similar material to make the joint between the two parts substantially moisture proof. Since the gears 23 are provided with two teeth for each numeral on the corresponding numeral wheel, it is possible to set the numeral wheel with the space between the numerals instead of one of the numerals itself being opposite the opening 60. If this should accidentally be done and the casing closed with the numeral wheel in this position, and power applied to the drive shaft, ordinarily no harm will be done further than the simple fact that the numeral wheel will be out of position by half a space. There is one condition, however, under which such a misplacement of the numeral wheel if not guarded against would produce a harmful result, and this will now be explained. From Fig. 13 it will be seen that the single tooth on the one-toothed bar 26 is of sufficient width to cover the space of two teeth and one opening of the gear 23. This is desirable because this single broad tooth operates between two of the four teeth on the pinion 34 and in order to permit operation of the device in either direction it is necessary to have the teeth broad enough to drive the pinion 34 in either direction. If two

teeth were used instead of one broad tooth, and the numeral wheel turned into position to bring the space between these two teeth opposite one of the teeth on the gear 34 (which would be in position to bring the space between the numeral 9 and the numeral 0 opposite the opening 60,) and the case closed in this position, the tooth on the numeral wheel 33 would be in position to be driven by the second tooth on the bar 26 upon rotation of the shaft 36. Such rotation would be impossible, however, since the teeth on the numeral wheel 33 would not be properly located relative to the Geneva disk 25 to permit rotation. If an attempt were made under these conditions to drive the counter, there would be danger of stripping the teeth from some of the gears. As the device is actually constructed, however, with one broad tooth instead of two on the bar 26, if a numeral wheel is set in the position described, that is with the space between the 9 and the 0 opposite the opening 60 and an attempt is made to close the casing, the tooth on the pinion 34 which is opposite the center of the bar 26, strikes the middle portion of the end of the bar or single tooth and prevents closing of the casing. As previously pointed out, it is desirable, however, that the casing be not closed under these conditions, and for this reason the central portion of the end of the bar 26 is left filled up instead of cutting it out to form two teeth. This arrangement prevents closing of the casing when the gears are turned in a position liable to produce damage if the casing were closed and the device operated.

In other words, although the carrying bars 26 must be constructed to produce a movement equivalent to two teeth in order to move the numeral wheels one digit, they are not provided with two separate teeth, but with a single broad integral member instead. This prevents the closing of the casing when the central portion of this broad tooth is opposite a tooth on the pinion 34. If these parts were permitted to mesh under these conditions, the teeth of pinion 33 would at the same time straddle the opening 40 to form a lock with the disk 25, and rotation of the numeral wheels would tend to move the three rigidly connected pinions 33, 34 and 35 while so locked, thus tending to break the pinion teeth. The construction employed prevents closing of the casing with the parts in this position.

In order to provide means for producing a one quarter revolution of the drive shaft when an article to be counted is moved past the counter, a star wheel shown in Fig. 8 is provided for contacting with the articles to be counted and for rotating the drive shaft. A wheel for this purpose must be light and strong and in order that it may be shipped in the same box with the counter, it should

be capable of being taken down or apart and assembled readily. The wheel used in this invention includes four arms 70, Figs. 18, 22 and 23. Each of these arms is made of a single piece of sheet metal bent in its middle as indicated at 71 and having the inner ends spaced apart so that the arms, when assembled form a closed triangle, thus giving a strong construction and light weight. A struck up portion 72 extends longitudinally of each section of the arms to insure rigidity. The inner ends of the arms are bent inwardly as shown at 73 and each inwardly bent portion is provided with two lugs 74. When the wheel is assembled, the inwardly bent portions of the arms abut against one another and the lug 74 of one arm registers with the lug 74 of the next arm, as shown in Fig. 18. Two disks 75 are provided, each having four openings 76 therein adapted to fit over the lugs 74 and hold the arms in place to constitute a complete wheel. The disks 75 are provided with central openings 77 adapted to receive the projecting end 78 of the sleeve 36. The sleeve 36 has a tapered portion 79 in position to enter the opening 77 in the inner disk 75 and a nut 80 is threaded on the end of the sleeve 36 and serves the double purpose of forcing the star wheel onto the sleeve and holding the disks 75 together. If it is desirable to adjust the position of the star wheel relative to the shaft, all that is necessary is to loosen the nut 88 which will leave the wheel free to be rotated about the sleeve 36. When the nut is again tightened, the wheel will be forced onto the tapered portion 79 and will again be in position to rotate the shaft 31.

In the bottom of the lower section 2 of the casing two countersunk openings 89 are provided for the reception of bolts or screws for fastening the counter in place on a machine in connection with which it is to be used.

It is believed that the operation of the device will be clear from the description of the parts and that a detailed explanation of the operation is unnecessary.

What I claim is:

1. In a counter, in combination a casing comprising two relatively movable sections, counting mechanism mounted in one of said sections, and driving mechanism for said counting mechanism mounted in the other of said sections.

2. In a counter, a casing consisting of two separable sections, a shaft carrying a series of counting units mounted in one of said sections, and driving mechanism adapted to coöperate with said counting units, when said casing is closed, to drive said counting units, carried in the other of said sections.

3. In a counter, a casing consisting of two separable sections, a shaft mounted in one of said sections, counting units mounted on said shaft having driving gears connected

therewith, a shaft mounted in the other of said sections having driving pinions mounted thereon and arranged to mesh with the driving gears of the counting units when said sections are brought together to form a closed casing and means carried by said last mentioned section for connecting said driving pinions with a source of power.

4. In combination, a casing section adapted to be secured to a machine, driving mechanism mounted in said section, a second section removably secured to said first section and counting mechanism carried in said second section independently of said first section and adapted to coöperate with the driving mechanism in said first section when said sections are united to form a complete casing.

5. In combination, a plurality of counter units, driving mechanism for said units, means for holding said units in operative connection with said driving mechanism and arranged to permit the removal of said units from said driving mechanism for adjustment of said units.

6. A counter comprising a plurality of numeral wheels, a shaft on which said wheels are adapted to be rotated, means for driving said numeral wheels, a support for said driving means, and means for supporting said numeral wheels independently of the support for said driving means and out of engagement with said driving means to permit adjustment of said numeral wheels.

7. In a counter, a casing having a flat bottom, a wall substantially at right angles to said bottom, a curved wall connecting the diagonally opposite edges of said first mentioned wall and said bottom, said casing being divided into two sections along a dividing surface extending substantially from the diagonally opposite edges of said first mentioned wall and said bottom, and means for detachably securing together the sections thus formed.

8. In a counter, a closed casing, a driving shaft mounted in the angle formed by two walls of said casing, counting mechanism carried on a shaft mounted in the portion of said casing diagonally opposite said driving shaft, said casing being divided into two sections along a plane extending from diagonally opposite corners of said casing and between said shafts, and means for pivotally and detachably securing said sections together.

9. In a counter, a casing having a closure therefor, driving mechanism mounted in said casing, and a latching device adapted when in one position to lock said closure and when in another position to prevent movement of said driving mechanism.

10. In a counter, a casing, a shaft mounted in said casing, driving pinions carried by said shaft, a cover for said casing and a

latch arranged to alternately hold said cover in closed position and to prevent movement of said pinions.

11. In a counter, a casing, a driving pinion mounted in said casing and a latch for said casing arranged to coöperate in one position with said pinion to prevent rotation thereof.

12. In a counter, a casing, a gear mounted 10 in said casing, a closure for said casing, a bar mounted in said casing, means carried by said bar for locking said closure when said bar is in one position and means carried by said bar for preventing movement 15 of said gear when said locking means is in released position.

13. In a counter, a casing having relatively movable sections, a gear carried in one of said sections, a coöperating gear carried 20 in another of said sections, means for holding said second mentioned gear from rotation, and a single device arranged to lock said casing in closed position and to prevent operation of said gear holding 25 means when in one position, and to permit operation of said gear holding means and to prevent movement of said first-mentioned gear when in another position.

14. In a counter, a driving pinion, a 30 counter unit adapted to be operated by said pinion, means for supporting said pinion and counter unit in separable engagement with one another, mechanism for holding said pinion and counter unit against accidental rotation when separated from one another, and means for moving said holding 35 mechanism into and out of operative position, and means for preventing separation of said pinion and counter when said holding mechanism is out of operative position.

15. In combination, a counter unit, a detent for holding said unit from accidental movement, and means for automatically preventing operation of said detent when said 45 counter unit is in operative position.

16. In a counter, a numeral wheel, a gear for driving said numeral wheel, a spring 50 detent for yieldingly preventing movement of said numeral wheel, and automatic means for preventing operation of said detent when said numeral wheel is in operating position.

17. In a counter, a driving shaft, a plurality of driving pinions loosely mounted 55 on said shaft, a second shaft, a plurality of counting units loosely mounted on said second shaft and having gears adapted to coöperate with said driving pinions, separable casing sections for carrying said 60 shafts, mechanism movable into one position wherein shifting of said driving pinions and said counting units is prevented and into another position to permit shifting of said counting units, and means, arranged 65 to move into and out of operative

position in synchronism with said movable mechanism, for preventing separation of said casing sections whenever said mechanism is in said last-mentioned position.

18. In a counter, a pair of separable casing sections; a pinion carried by one of said sections, a gear carried by the other of said sections and arranged to coöperate with said pinion, an intermittent gear lock for preventing accidental rotation of said gear and 70 pinion when said sections are in closed position, means for preventing accidental rotation of said gear and pinion when said sections are separated from one another, and a catch constrained to move into and out of operative position, in timed relation with the movement of said last-named means, for preventing separation of said sections whenever said last-named means are in inactive position.

19. In a counter, a casing comprising a pair of separable sections, a shaft carried by one of said sections, driving pinions loosely mounted on said shaft, a bar carried by said section and adapted in one position to lock said separable sections in closed position and to permit separation of said sections when in another position, and means on said bar for preventing rotation of said pinions when said bar is in said second 95 mentioned position.

20. In a counter, a plurality of counting units having numeral wheels, spring detents for preventing accidental rotation of said wheels but arranged to permit rotation thereof under sufficient turning moment, means for closing said casing and means for automatically disengaging said detents from said wheels when said casing is closed.

21. In a counter, a casing having separable sections, a drive shaft carried by one of said sections, a driving pinion secured to said drive shaft to rotate therewith, a counting unit adapted to mesh with said driving pinion when said sections are in closed position, a pinion loosely mounted on said drive shaft and adapted to be operated once for every revolution of said counting unit, a second counting unit adapted to be operated by 110 said second mentioned pinion, and means for preventing accidental movement of said pinion and said counters when not in operative connection with one another.

22. In a counter, a shaft, a plurality of 120 counting units mounted on said shaft, each unit including a numeral wheel, means for supporting said units in an operative position, means for preventing accidental rotation of said units when in such position, 125 driving mechanism for said units, a device for locking said units in operative relation with said driving mechanism, and means controlled by said locking device for releasing said means for preventing acci- 130

dental rotation of said units when said units are in engagement with said driving means.

23. In a counter, a casing comprising a pair of separable sections, a driving shaft carried by one of said sections, driving pinions loosely mounted on said driving shaft, a latch bar carried by said section and arranged to lock said casing in closed position and to prevent rotation of said driving pinions when said casing is not locked in closed position; a shaft carried by the other of said sections, a plurality of counting units loosely mounted on said shaft and adapted to be rotated independently of one another when said casing is in open position, and spring detents for preventing accidental rotation of said units when said casing is in open position but arranged to permit free rotation thereof when said casing is closed.

24. A counter comprising a plurality of relatively movable numeral wheels, driving mechanism for said numeral wheels arranged to be disconnected therefrom to permit adjustment of said numeral wheels, and means for holding said numeral wheels in operative position relative to one another while said numeral wheels are disconnected from said driving means.

25. A counter comprising a plurality of numeral wheels, driving mechanism for said numeral wheels, and a casing for said numeral wheels having an opening therein to permit readings of said numeral wheels, said casing being arranged to hold said numeral wheels in operative position relative to one another and to said opening and disconnected from said driving mechanism for adjustment of said numeral wheels.

26. In a counter, a shaft, a plurality of numeral wheels mounted on said shaft having means thereon for establishing communication with a source of power, a drive

shaft, driving gears on said drive shaft, and separate means for carrying said shafts, 45 said separate means being movable relative to one another to operatively connect and disconnect said numeral wheels and said driving gears.

27. In a counter, a casing arranged to be 50 opened and closed, a driving gear for said counter arranged to be moved out of operative relation when said casing is opened, means for holding said gear, while said casing is open, in position to properly return 55 into operative relation when said casing is again closed, and a device for releasing said holding means to permit rotation of said gears when said casing is closed.

28. In a counter, a casing arranged to 60 be opened and closed, gearing for said counter arranged to be moved out of and into mesh when said casing is opened and closed respectively, said gearing being adjustable when out of mesh, and means for 65 preventing the closing of said casing when said gearing is set in position to mesh improperly.

29. In a counter, a casing arranged to be 70 opened and closed, gearing for said counter arranged to be moved out of and into mesh when said casing is opened and closed respectively, said gearing being adjustable when out of mesh, and means on said gearing to prevent meshing thereof when said 75 gearing is adjusted to a position in which, if caused to mesh, it would lock on rotation thereof.

In testimony whereof I have signed my name to this specification, in the presence 80 of two subscribing witnesses, on this 11 day of June A. D. 1915.

MICHAEL J. MILMOE.

Witnesses:

HERBERT J. SANVEYL,
G. J. BECKER.
